SECONDARY RACK

George McD. Johns, Sappington, Mo., assignor to
 Smithjohns, Inc., Sappington, Mo., a corpora-
 tion of Missouri

Application June 24, 1940, Serial No. 342,137

12 Claims. (Cl. 248—67.7)

This invention relates generally to electric line equipment and, more particularly, to a certain new and useful improvement in devices commonly designated secondary racks for supporting telephone and electric transmission lines and the like.

My invention has for its primary objects the provision of a rack of the type and for the purposes stated which is simple, durable, and rugged in structure, which may be cheaply and economically manufactured, which may be quickly and conveniently installed, and which comprises support-engaging fixtures and insulator-supporting brackets uniquely constructed for rack enlargement or for selective disposition of the brackets for facile meeting practically all pole or line requirements.

And with the above and other objects in view, my invention resides in the novel features of form, construction, arrangement, and combinations of parts presently described and pointed out in the claims.

In the accompanying drawings (2 sheets), Figures 1, 2, and 3, are perspective views of, respectively, the co-operable parts or members, namely, attachment-fixture, insulator-bracket or hanger, and insulation wire-engaging spool, of a so-called secondary rack embodying my present invention;

Figure 4 illustrates in longitudinal section a pair of the racks in associated or gang relation;

Figure 5 is a fragmentary front elevational view of the ganged or associated racks of Figure 4;

Figures 6, 7, and 8 are transverse sectional views of the rack taken approximately along the lines 6—6, 7—7, and 8—8, respectively, Figure 4; and

Figure 9 illustrates in side elevation the manner of attachment of an assembled insulator and hanger directly to a wall, the attachment fixture being omitted.

Referring now in more detail and by reference characters to the drawings, which illustrate a preferred embodiment of my invention, the rack includes an oblong-rectangular fixture or attachment base A constructed preferably as a unitary casting from malleable iron or other suitable metallic material and comprising preferably integrally a pair of approximately parallel longitudinal or side walls 1 connected or joined at their one or upper end by a transverse wall or bar 2 having, reference being made to Figures 1 and 4, a lower face 3 presented obliquely inwardly and downwardly intermediate the walls 1. At their lower end, the walls 1 are formed with obliquely

downwardly and inwardly presented registering extensions 4 providing a notch, as at a, therebetween and the lower or outer end face of the walls 1, the extensions 4 being connected or joined by a second transverse wall or bar 5 having an obliquely inwardly and downwardly outer face 6 and provided in its top margin with a cut-out or notch, as at b, as best seen in Figure 1 and all for purposes presently appearing.

10 Suitably spaced at their one or upper end from the upper end-wall 2, so as to provide an opening, as at c, at the upper end of the base A, are so-called arcuate beads 7, which are presented inwardly from and with respect to the upper margins of, and which extend longitudinally of the fixture for some distance along, the walls 1, and joining the beads 7 transversely of the fixture, is a top wall or web 8 having in suitably spaced relation longitudinally of the fixture an annular opening or aperture, as at d, and an elliptical opening or aperture, as at e, and provided centrally at its lower margin with a downwardly presented bendable or malleable tongue 9, the channels f of the beads 7 providing concealed ways or tracks adjacent the opposite inner faces of the walls 1, all as best seen in Figures 1 and 8 and for purposes presently appearing.

Throughout the remainder of their length from approximately the transverse plane of the lower end of the tongue 9, the walls 1 are extended forwardly, as at 1^a, and such extensions 1^a are laterally formed upon their free margins with pairs or sets of opposed tongues 10—10 and 11—11 suitably disposed in spaced tandem relation longitudinally of the fixture, the tongues of each pair being suitably spaced one from the other transversely of the fixture in the provision of aligning wedge-shaped ways, as best seen in Figure 1 and for purposes presently appearing.

40 Preferably for symmetry and strength, the pairs or sets of tongues 10, 11, are joined longitudinally of the fixture by intermediate front wall flanges 12 presented laterally in opposed relation from the wall-extensions 1^a at their upper margin, and the tongues 10 are preferably re-enforced or strengthened by triangular webs 13 disposed between the under faces of the tongues 10 and the inner faces of the walls 1, as best seen in Figure 1.

50 Extending longitudinally of the fixture from the base of the oblique face 6 of the lower end wall 5 and provided on its upper face and marginally from the side-wall extensions 4 with parallel ribs 14, is a suitably elongated tongue in the form of a web 15 disposed in such plane for end-

wise projection through the opening *c* and under the web *8* of, and for gang-connection with, a companion fixture for enlarging a particular rack, as shown in Figure 4, the tongue or web *15* having an opening, as at *g*, for registration with opening *d* for accommodating a securing-bolt *16* for fastening the two fixtures in endwise rack-elongating or gang relation, and the ribs *14*, in such gang-assembly, fitting smoothly and snugly within the channels *f*. In such interfitting engagement, it may here be said, the end-bar or wall *2* is also snugly accommodated by the somewhat angular notch or recess *a*, as shown.

Along their rearwardly presented longitudinal margins, the side walls *1* are provided with narrow lateral flanges *17* and a pair of outwardly presented apertured ears *18* preferably suitably continuously beveled on their under face for snugly fitting upon the arcuate surface of, and attachment to, a telephone post or the like *P*, as best seen in Figures 4 and 5. As shown particularly in Figure 5, the ears *18* accommodate suitable bolts, as *18^a*, for convenient attachment of the fixture *A* to a supporting structure, as, for instance, the post *P*, the connection of the fixture *A* upon the post being supplemented by an additional bolt *18^b* preferably projected into the post through the opening *e*, substantially as shown.

Co-operable with the fixture *A*, is a clevis-shaped hanger or bracket *B* preferably in the form of a U-shaped malleable casting integrally including a bight *19* and opposed parallel legs *20, 21*, preferably annularly enlarged at their free outer ends in the provision of insulator-receiving enlargements or so-called eyes *22, 23*, receiving registering apertures *24*.

Upon its outer or rearwardly presented face, the bight *19* is suitably thickened in the provision of a central boss or lug *25* joined by diametrically opposite fillets or necks *26* to enlargements *27, 28*, marginally undercut in the provision of wedge-shaped grooves or ways *29, 30*, complementary in shape to, and for hanger-engagement with, the tongues *10, 11*, of the fixture *A*, as best seen in Figures 4 and 5.

Adjacent the bight *19* and on its outer face, the clevis-leg *21* is also provided with a like enlargement *31*, and the enlargement *31* and the eye *23* are similarly marginally undercut in the provision of wedge-shaped grooves *32, 33*, for also selectively accommodating, and for engagement with, the fixture tongues *10, 11*, as presently more fully appears.

Upon their inner face, the hanger-legs *20, 21*, are centrally provided longitudinally with strengthening ribs *34*, and joining the respective eyes *22, 23*, and the respective way-providing enlargements *27, 28, 31*, upon the outer face of the hanger *B*, are preferably additional re-enforcing ribs *35*, all as best seen in Figure 2 and for purposes presently more fully appearing.

Sized for fitting snugly intermediate the opposed faces of the clevis eyes *22, 23*, is a spool-shaped insulator *C* constructed preferably of porcelain or other suitable dielectric material and provided with an axial bore, as at *36*, for accommodating a supporting shaft *37* for projection endwise into the registering apertures *24*, and fitting lengthwise in slots or recesses, as at *38*, provided in the inner face of the hanger-eye *22* provided in the inner face of the hanger-eye *22* and engaging the shaft *37*, is a locking-pin *39*.

The fixture *A* and insulator-equipped hanger or bracket *B* are thus co-operatively uniquely

formed for selective detachable engagement, the bracket *B* either at its bight *19* or at its leg *21*, being engageable with the fixture tongues *10, 11*, with the insulator *C* correspondingly disposed, as may best meet the requirements of the line or installation, either in parallel or right-angular relation to the fixture *A*, as shown in Figure 4, the tongues *10, 11*, being engaged either in the ways *29, 30*, or *32, 33*, as the case may be. In either arrangement, the arcuate portion *35^a* of an abutting outer rib *35* will be snugly accommodated by the recess or notch *b* in the fixture wall *5*, and when so selectively engaged with the fixture *A*, the fixture-tongue *9* may be bent outwardly by means of a screw driver or other suitable instrument into endwise abutting engagement with the then outwardly presented face of either the enlargement *27* or the eye *23*, as the case may be, for preventing accidental displacement of the bracket *B*, all as best seen in Figures 4 and 6.

The boss or lug *25* and bight *19* are preferably provided with a continuous opening, as at *40*, and hence, I may add that, to meet line or installation requirements, the insulator-equipped clevis or bracket *B* may be secured directly upon a post, wall, or the like by means of a conventional lag-bolt *41* projected thereinto through such opening *40*, as best seen in Figure 9.

The rack efficiently fulfills and performs in every respect the objects stated and all its intended functions, and it should be understood that changes and modifications in the form, construction, arrangement, and combination of the several parts of the rack may be made and substituted for those herein shown and described without departing from the nature and principle of my invention.

Having thus described my invention, what I claim and desire to secure by Letters Patent is:

1. A secondary rack including, in combination, a fixture adapted for securement to a post, wall, or similar supporting structure, an insulator-hanger removably mounted in the fixture, and a bendable tongue on the fixture adapted, upon being bent outwardly, to engage and lock the hanger in place.

2. A secondary rack including, in combination, a fixture adapted for securement to a post, wall, or other similar structure, said fixture having a plurality of projecting lugs, an insulator-hanger having a plurality of sets of recesses each for engagement with the fixture lugs for holding the hanger upon the fixture in different respective positions, and a bendable tongue on the fixture adapted, upon being bent outwardly, to engage and lock the hanger in place.

3. A secondary rack adapted for supporting an insulator bracket, said rack comprising an elongated body member having means upon its outwardly presented face for engagement with the bracket, said body member further being provided at one end with socket-forming means including a wedge-shaped bar and at its other end with tongue means complementarily shaped with respect to the socket means and having a transverse recess complementarily shaped with respect to the bar in such a manner that the tongue of any one body member may be snugly engaged in the socket means of another identical body member for disposing a plurality of fixtures in endwise aligned units to accommodate a plurality of insulator brackets.

4. In a secondary rack, a base comprising side walls rigidly joined in spaced parallel relation

and laterally formed upon their upper margin with pairs of opposed tongues disposed in spaced relation longitudinally of the base and the tongues of each pair being spaced one from the other transversely of the base in the provision of aligning ways for supporting engagement with an insulator hanger.

5. A secondary rack including an oblong rectangular base comprising side walls rigidly joined in spaced parallel relation and laterally formed upon their upper margin with pairs of opposed tongues disposed in spaced relation longitudinally of the base and the tongues of each pair being spaced one from the other transversely of the base in the provision of aligning ways, in combination with an insulator-hanger having a marginally undercut enlargement for engagement upon the base with said tongues.

6. A secondary rack including a base comprising side walls rigidly joined in spaced parallel relation for a portion of their length by a transversely disposed top wall, said side walls, in another portion of their length, being extended forwardly and laterally formed upon the upper margin of said extensions with pairs of opposed tongues disposed in spaced relation longitudinally of the base and the tongues of each pair being spaced one from the other transversely of the base in the provision of aligning ways, in combination with an insulator-hanger having a marginally undercut enlargement for engagement upon the base with said tongues.

7. A secondary rack including an oblong rectangular base comprising side walls rigidly joined in spaced parallel relation for a portion of their length by a transversely disposed top wall, said side walls, in another portion of their length, being extended forwardly and laterally formed upon the upper margin of said extensions with pairs of opposed tongues disposed in spaced relation longitudinally of the base and the tongues of each pair being spaced one from the other transversely of the base in the provision of aligning ways, in combination with an insulator-hanger of substantially U-shape having upon a member thereof a pair of spaced outwardly presented and marginally undercut enlargements for engagement upon the base with said tongues.

8. A secondary rack including an oblong rectangular base comprising side walls rigidly joined in spaced parallel relation for a portion of their length by a transversely disposed top wall, said side walls, in another portion of their length, being extended forwardly and laterally formed upon the upper margin of said extensions with pairs of opposed tongues disposed in spaced relation longitudinally of the base and the tongues of each pair being spaced one from the other transversely of the base in the provision of aligning ways, in combination with an insulator-hanger having sets of outwardly presented and marginally undercut enlargements disposed in angular relation one set to the other for respective engagement with said tongues for disposing the hanger in selected corresponding angular relation to and upon the base.

9. A secondary rack including an oblong rectangular base comprising side walls rigidly joined in spaced parallel relation for a portion of their length by a transversely disposed top wall, said side walls, in another portion of their length, being extended forwardly and laterally formed upon the upper margin of said extensions with pairs of opposed tongues disposed in spaced relation longitudinally of the base and the tongues of each pair being spaced one from the other transversely of the base in the provision of aligning ways, in combination with an insulator-hanger having sets of outwardly presented and marginally undercut enlargements, the enlargements of each set being in spaced aligning tandem relation and the respective sets of enlargements disposed in angular relation one set to the other for respective engagement with said tongues for disposing the hanger in selected corresponding angular relation to and upon the base.

10. A secondary rack including an oblong rectangular base comprising side walls rigidly joined in spaced parallel relation for a portion of their length by a transversely disposed top wall, said side walls, in another portion of their length, being extended forwardly and laterally formed upon the upper margin of said extensions with pairs of opposed tongues disposed in spaced relation longitudinally of the base and the tongues of each pair being spaced one from the other transversely of the base in the provision of aligning ways, in combination with an insulator-hanger of substantially U-shape having upon both the bight and a leg thereof outwardly presented and marginally undercut enlargements for respective engagement with said tongues for disposing the hanger in selected angular relation to and upon the base.

11. In a secondary rack, an insulator-hanger of substantially U-shape having upon both the bight and a leg thereof outwardly presented and marginally undercut enlargements for respective slidable engagement with a base for disposing the hanger in selected angular relation to the base.

12. A secondary rack including a base comprising side walls rigidly joined in spaced parallel relation for a portion of their length by a transversely disposed top wall, said side walls, in another portion of their length, being extended forwardly and laterally formed upon the upper margin of said extensions with pairs of opposed tongues disposed in spaced relation longitudinally of the base and the tongues of each pair being spaced one from the other transversely of the base in the provision of aligning ways, in combination with an insulator-hanger having a marginally undercut enlargement for engagement upon the base with said tongues, and a bendable tongue projecting from said top wall for securing engagement with the insulator-hanger.
